Des. 810

Be it known that we, N. G. Bedder, and M^m L. Sanderson, of the city of Troy in the County of Rensselaer, and State of New York, have invented or produced a new and original design for Stoves; and we do hereby declare that the following is a full and exact description of the same, reference being had to the accompanying drawings, making part of this specification, in which

Fig. 1. is a side plate with doors;

Fig. 2. an upper front plate;

Fig. 3. a portion of hearth plate.

Fig. 5. a foot.

Fig. 6. a back plate.

Fig. 7. a lower front plate.

Fig. 8. a portion of bottom plate.

Fig. 9. a portion of top plate

a, b, c, d, are ornamental panels; e, f, g, h, i, o, are moldings; j, k, l, m, are ornamental borders, composed of a combination of scroll work and moldings; n, is an ornamental border of bosses and shell work; p, p, q, q, are ornaments. r, r, r, s, t, are ornamental edges.

What we claim as our invention, and desire to secure by Letters Patent, is the design and configuration of the ornaments and moldings, as herein described, forming an ornamental design for stoves.
